Primary Examiner — Rebecca Tsehay

(57) **CLAIM**

The ornamental design for a hair drier, as shown and described.

DESCRIPTION

Fig. 1.1 is a perspective view of the hair drier according to an embodiment of the present invention;

Fig. 1.2 is a front view of the hair drier of Fig. 1.1;

Fig. 1.3 is a rear view of the hair drier of Fig. 1.1;

Fig. 1.4 is a left-side view of the hair drier of Figure 1.1;

Fig. 1.5 is a right-side view of the hair drier of Fig. 1.1;

Fig. 1.6 is a top of the hair drier of Fig. 1.1;

Fig. 1.7 is a bottom view of the hair drier of Fig. 1.1;

Fig. 1.8 is a perspective lower front view of the hair drier of Fig. 1.1;

Fig. 1.9 is a perspective lower rear view of the hair drier of Fig. 1.1; and

Fig. 1.10 is a perspective rear top view of the hair drier of Fig. 1.1.

The broken lines in the drawings depict portions of the hair drier that form no part of the claimed design.
